DAVID THOMAS, OF HINGHAM, MASSACHUSETTS.

Letters Patent No. 80,575, dated August 4, 1868.

IMPROVEMENT IN FRICTION-NIPPER.

The Schedule referred to in these Letters Patent and making part of the same.

TO ALL WHOM IT MAY CONCERN:

Be it known that I, DAVID THOMAS, of Hingham, in the county of Plymouth, and State of Massachusetts, have invented an Improved Nipper-Feed for vessels' windlasses and other rotating bodies; and I do hereby declare that the following, taken in connection with the drawings which accompany and form part of this specification, is a description of my invention sufficient to enable those skilled in the art to practise it.

This invention, though specially designed and adapted for rotating vessels' windlasses, is also applicable to rotate various other cylindrical bodies and wheels, and it may be considered as an improvement on the windlass-gear known as the "Scotch nipper," with reference to which it will be described.

In the drawings—

Figure 1 shows in section the "Scotch nipper," *a* being the ring which is secured to the windlass-body, and on which the "nipper" operates to turn the windlass-body, the section of the ring *a* being shown in Figure 2.

The nipper is made up of two parts or cheeks, which are bolted together, and are capable of sliding upon the outer flange of the ring *a*, the cheeks having jaws which adjoin the inner surface of the outer flange.

Between the cheeks *b*, and pivoted thereto, is a lever, *c*, the short end of which is eccentric to the pivot of the lever, so that as the long arm of the lever is lifted, the lever turns on its pivot, bringing the eccentric or inclined end of the lever upon the outer surface of the outer flange of the ring *a*, causing the jaws of the nipper to hug closely to the inner surface of the outer flange of said ring, thus gripping or clamping the ring by the nipper, so that further movement of the lever in an upward direction causes the ring to turn on its axis, carrying with it the windlass to which the ring is fixed.

When the lever is pushed downward, it will be evident that it will turn slightly on its pivot, such turning slackening the hold of the nipper on the windlass-ring, so that the whole of the nipper, cheeks, and lever, will gravitate downward, sliding on and around the outer flange of ring *a*.

Now the objections to this well-known nipper, which it is the object of my invention to avoid, are these:

First. The short end of the lever wears a groove in the outer surface of the flange of the ring *a*, and the place of contact of said end of the lever being small, this also wears rapidly, so that the apparatus very soon needs repairs, which have to be accomplished either by making a new lever or by reforging its short end.

Second. Great care has to be paid to the proportions of the short end of the lever, for if its eccentricity is too great, it will not grip with sufficient power, and the nipper will slip under stress, and if the eccentricity is too small, it takes considerable movement of the long arm of the lever to obtain a grip, which, when obtained, is not easily loosened, and very slight wear of the parts will render the nipper wholly inoperative.

Now my invention consists in making a groove, fork, or crotch in the short arm of the lever, and in applying a shoe which extends across the outer face of the outer flange of ring *a*, so that the crotch of the short arm of the lever shall operate on the shoe, as seen in Figure 3, which is a sectional view similar to fig. 1.

In this fig. 3, the conformation of the short arm of the lever is clearly shown, its crotch or fork fitting on the shoe *d*, which extends across the outer flange of the ring *a*, and fits loosely into shallow depressions made in the inner surfaces of the cheeks *b*, so that the shoe is held in proper position for the action thereon of the lever *c*.

It will be obvious that by the use of the shoe extending entirely across the outer surface of the outer flange of ring *a*, the wearing-surface is greatly increased in area, and that no groove can be worn by the action of the improved nipper into the ring *a*. As the movement of the crotch of the lever on the apex of the shoe is very slight, the wear at that point will be almost imperceptible, and it will be readily seen that the grip of the improved nipper is certain, and is obtained and released with but slight vibration of lever *c* on its pivot *e*, while the power of the grips obtained will be in exact ratio to the distance from pivot *e* of the apex of the shoe, as compared to the length of the long arm of the lever.

When, after long and severe use, wear enough takes place to produce considerable lost motion of the long arm of the lever in obtaining a grip, the difficulty is easily remedied by placing in the nipper-jaws a new and

slightly thicker shoe, or for temporary purposes a thin piece of sheet metal may be inserted between the crotch of the lever and the apex of the shoe.

Figure 4 shows a common method of working a ship's windlass by the application of a "Scotch nipper," operated by a brake-lever, my improvement being also capable of being operated in the same manner, as well as variously otherwise.

I claim, in friction-nipper feeds, the employment of a shoe in connection with the notched lever, cheeks, and flanged ring, so as to operate substantially as described.

DAVID THOMAS.
